SHAVING CREAM APPLICATOR

Maxwell Tonge, Chicago, Ill.

Application December 11, 1950, Serial No. 200,176

1 Claim. (Cl. 15—132.5)

1 The present invention relates to certain new and useful improvements in applicators for shaving cream and has more particular reference to the type of applicator which, once the usual screw cap is removed from the usual collapsible tube, said applicator may be substituted for said cap.

More specifically, the invention has to do with a novel adapter unit with a screw threaded attaching collar applicable to the usual screw threaded discharge neck on the aforementioned tube, said adapter being provided with spaced parallel applicator rollers.

As the preceding statements imply, applicators with freely idling roller means for use on conventional collapsible tubes are not new. It is therefore an object of the present invention to structurally, functionally and otherwise improve on prior art applicator constructions.

Another object of the invention is to provide a simple, practical and economical attachment type applicator in which manufacturers and users will find their essential requirements fully met, contained and satisfactorily available.

More specifically, novelty is predicated on an adapter which takes the form of a hollow or dished-type receiver, said receiver being provided with a discharge slot which in turn has spaced parallel rollers associated therewith, said receiver being provided along opposite longitudinal sides with outstanding flanges to assist in spreading the cream on the face of the user and expediting free and easy movement of the rollers over the surfaces to be treated.

Then, too, novelty is predicated on a type of roller-equipped spreader and adapter construction wherein an easily applicable and removable cover may be employed to lid over and close the roller-equipped slot when the applicator is not in use.

Other objects and advantages will become more readily apparent from the following description and the accompanying sheet of illustrative drawings.

In the accompanying sheet of drawings, where-in like numerals are employed to designate like parts throughout the views:

Figure 1 is a fragmentary perspective view of a conventional collapsible tube, with the usual screw cap removed and the applicator in place, the cover being shown in its open or removed position;

Figure 2 is an elevational view with the cover off;

Figure 3 is a fragmentary view with the parts shown in section and elevation to bring out cer-

tain of the details and their arrangement, the section being on the line 3—3 of Figure 4, looking in the direction of the arrows; and,

Figure 4 is a view at right angles to that identified as Figure 3, the section being on the line 4—4 of Figure 3, looking in the direction of the arrows.

Referring now to the drawings by way of reference numerals and accompanying lead lines, the collapsible tube, which is a conventional tube used for marketing and dispensing shaving cream, is denoted by the numeral 6 and is provided with the usual screw threaded discharge neck or nipple 8. The applicator attachment is denoted generally by the numeral 10. It is adapted to be produced on a mass production basis and may be made from appropriate moldable materials such as for example, so-called commercial plastics. The adopted structure takes the form of a simple, readily applicable and removable attachment which is composed of two components or units; namely, the adapter and the cover or lid. The adapter is molded from one piece and includes a dished elongated receiver 12. The receiver has longitudinal walls 14 of proper curvature and formation and has relatively narrow flat end walls 16—16. A screw threaded neck 20 is employed at the bottom of the well in the receiver and this is adaptable to ready attachment to the neck 8. There is a discharge slot 22 and fitted into this and turnable freely therein are spaced parallel applicator rollers 24—24. These are provided with appropriate journals mounted for rotation in suitable bearings provided therefor in the transverse end walls 16, as best shown perhaps in Figure 4. The side walls are also provided with outstanding members which may be conveniently defined as flanges 26—26. The flanges are tapered in cross section and serve as spreaders along the longitudinal reaches of the slot 22. The upper edges of the transverse walls are curvate as shown at 28 and maintain effective substantially airtight contact with the face of the user. The aforementioned cover is denoted by the numeral 30 and this takes the form of a suitable plate or lid having a curvate center portion 32 and having marginal hook-shaped flanges 34—34 which cooperate with and engage over the narrow edge portions of the aforementioned spreader flanges 26.

When the cover 30 is slid off the applicator head, as shown in Figure 2, the latter is in readiness to function. The cream is compressed from the tube into the chamber or well of the receiver and is applied in an obvious fashion by the idling

3

rollers in the discharge slot 22. The surfaces of the flanges 26—26 facilitate guiding and riding the rollers over the surface of the face and also assist in spreading the cream evenly and these flanges also provide satisfactory mounts for the readily attachable and detachable cover. The upstanding curvate edges 28 function as shoes and maintain liquid tight contact with the face of the user.

It is thought that persons skilled in the art to which the invention relates will be able to obtain a clear understanding of the invention after considering the description in connection with the drawings. Therefore, a more lengthy description is regarded as unnecessary.

Minor changes in shape, size and arrangement of details coming within the field of invention claimed may be resorted to in actual practice, if desired.

Having described the invention, what is claimed as new is:

An attachment for the discharge neck of a collapsible tube comprising an elongate hollow head having opposed longitudinal side walls and interconnecting transverse end walls, said end walls being substantially flat and in spaced parallelism, said side walls being dished and cooperating with the end walls in defining a receiver and collector for cream dispensed by way of said discharge neck into said receiver, said receiver being provided at the center of its intake portion with an attaching neck, the upper edges of

5 said side walls being provided with outstanding complementary flanges which are commensurate in length with the over-all length of the receiver and which are approximately V-shaped in transverse cross-section, the vertex edges of said flanges being relatively thin and disposed in directions away from said side walls, the upper edges of the end walls projecting above the upper edge portions of the side walls and being substantially flush with the uppermost surfaces of 10 said flanges and providing shoe members which are adapted to have riding contact with the user's face, and a pair of rollers mounted in the discharge portion of said receiver, said rollers being spaced from one another and also spaced from and approximately paralleling the inner surfaces of said side walls and being in permanent non-shifting relationship in respect to each other and said side and end walls, said flanges being 15 adapted to accommodate a readily attachable and detachable cover plate.
